DESIGN FOR A NEGLIGEE OR SIMILAR ARTICLE

Alice Macksoud, New York, N. Y.

Application May 3, 1945, Serial No. 119,370

Term of patent 7 years

(Cl. D3—26)

To all whom it may concern:

Be it known that I, Alice Macksoud, a citizen of the United States of America, residing in New York city, county of New York, and State of New York, have invented a new, original, and ornamental Design for a Neglige or Similar Article, of which the following is a specification, reference being had to the accompanying drawing, forming part thereof, wherein,

I claim:

The ornamental design for a neglige or similar article, substantially as shown.

ALICE MACKSOUDE.
